(57) **CLAIM**

The ornamental design of an ergonomic keypad, as shown and described.

DESCRIPTION

FIG. 1 is a front plan view of an ergonomic keypad of the present invention;

FIG. 2 is a top plan view of the ergonomic keypad of FIG. 1.

FIG. 3 is a bottom plan view of the ergonomic keypad of FIG. 1.

FIG. 4 is a right side elevation view of the ergonomic keypad of FIG. 1.

FIG. 5 is a left side elevation view of the ergonomic keypad of FIG. 1.

FIG. 6 is a back plan view of the ergonomic keypad of FIG. 1; and,

FIG. 7 is a top perspective view of the ergonomic keypad of FIG. 1.

1 Claim, 6 Drawing Sheets

FIG. 1

FIG. 2

FIG. 3

FIG. 4

FIG. 5

FIG. 6
